Inventor.

UNITED STATES PATENT OFFICE.

JOHN H. TIFFANY, OF DIMOCK, PENNSYLVANIA.

DRAFT ATTACHMENT FOR VEHICLES.

SPECIFICATION forming part of Letters Patent No. 381,183, dated April 17, 1883.

Application filed June 13, 1887. Serial No. 241,101. (No model.)

To all whom it may concern:

Be it known that I, JOHN H. TIFFANY, a citizen of the United States, residing at Dimock, in the county of Susquehanna and State 5 of Pennsylvania, have invented certain new and useful Improvements in Draft Attachments for Vehicles; and I do hereby declare the following to be a full, clear, and exact description of the invention, such as will enable 10 others skilled in the art to which it appertains to make and use the same.

My invention relates to means for adjusting and balancing a cart or other vehicle; and it consists in the combination, with the body of 15 a vehicle and the draft appliances, of an attachment connecting the said body to the draft, so as to raise the front end of the vehicle when too low and lower it when too high and adjust it at the proper position by the draft of the 20 team and tension of the harness.

It is illustrated in the accompanying drawings, in which Figures 1 and 2 are side elevations, and Fig. 3 a plan.

I have illustrated this invention as applied 25 to a class of vehicles for which I obtained Letters Patent Nos. 297,876 and 308,933, of 1884.

In the drawings, A represents the top of the body or frame of the vehicle; a, the bottom; B, central large wheels; C, a tongue; D, the whiffle-trees; F, a crank-axle; G, a runner, and H, small-wheels at opposite end of the vehicle; J, draft rod, chain, or cord, each end of which is attached to the upper front end corners of body, and the central portion to pass through 30 or be attached to a loop or clevis in the whiffle-tree or doubletree.

K is a draft rod, chain, or cord from bottom of body to whiffle-trees. When rods are used, they must be pivoted to the body of the vehicle. 40

The top and bottom draft rods or chains, J and K, must be of a proper length, so as to draw on them all at the same time when the vehicle is adjusted or balanced properly or at 45 the desired angle with the tongue. When the front end of the body is low, as shown in Fig. 2, the draft will be from the bottom rod or chain, which will raise the front end of the vehicle, and the upper adjusting device will be loose, as shown. When the front end of the body is too high, the draft will be from the top, which will lower it. The tension of the 50

harness upon the top or bottom of the body is the same as the draft of the team, as before explained, and helps to adjust and balance it. 55

N represents a spring, of elastic wood, metal, or other material, used to convey the weight of the thills, tongue, neck-yoke, or other weight from the team to the front end of the body or frame of the vehicle. The support or 60 fulcrum of the spring should be near the point where the tongue unites with the vehicle.

The spring tongue-support herein shown and described is made the special subject of my application No. 267,830, filed March 20, 65 1888.

When the front end of the vehicle is low, as shown in Fig. 2, the tongue-support does not convey the weight of the tongue, &c., to the front end of the vehicle; but about the time 70 the vehicle comes to a horizontal position, or at a desirable angle with the tongue the spring-support transfers the weight of the thills or tongue, whiffle-trees, harness, or other weight carried by the team to the front end of the vehicle, which tends to prevent the front end of the vehicle from rising too high, whereby the vehicle is better adjusted at the desired position. Another object of the spring-support is 75 thus to prevent the thills or tongue rising, so as to interfere with the team when the front end of the vehicle passes a large obstruction or when raised very high by other means.

I do not confine myself to the form of spring herein described; but any form of support that 85 will relieve the weight of the thills or tongue, whiffle-trees, neck-yoke, harness, and other weight from the team and transfer it to the front end of the vehicle when at the proper height and will not materially interfere with 90 the team when the front end of the vehicle is high will be comprised by my invention. I do not wish to confine myself to the draft-rods or chain-adjuster as before described, but to include any form of draft-adjuster to draw 95 from the top and bottom that will adjust and balance the vehicle.

I am aware that it is old to use spring tongue-supports on wagons; but I am not aware that a spring-support has been used 100 with a cart or other vehicle adjusted and balanced in manner and by the means herein described.

What I claim is—

1. In combination with the body of a vehicle and the draft appliances, an attachment consisting of rods, chains, or cords connecting the said body to the draft, whereby the body is balanced by the tension of the draft upon said attachment, substantially as described.

2. In combination with a vehicle-body, the tongue, and elastic tongue-support, the whiffletrees, and the adjusting device attached to

the top and bottom of the body and to the whiffletrees, substantially as and for the purpose described.

In testimony whereof I affix my signature in presence of two witnesses.

JOHN H. TIFFANY.
